COMBINED RESISTOR AND SHUNT SWITCH

Ira E. McCabe, Chicago, Ill.

Original application July 31, 1933, Serial No. 683,037. Divided and this application February 11, 1935, Serial No. 5,931

5 Claims. (Cl. 201—48)

This invention relates to improvements in switching systems and more particularly to a combined resistor and shunt switch for use in such a system. This application is a division of 5 this applicant's prior copending application Serial No. 683,037, filed July 31, 1933.

It is an object of this invention to provide an electric switch so constructed that when the circuit is first established therethrough to include 10 an electrical resistance in said circuit and upon operation of the switch to shunt out the resistance and allow the full current to pass therethrough. It is a further object of this invention to include a resistor in a mercury tube switch 15 which will be shunted out when the switch has been tilted to cause the mercury to contact the electrodes thereof.

Such combined resistor and shunt switches are of advantage when delayed action is desired in 20 controlling the operation of an electric motor and more particularly in connection with controlling reversing motors as disclosed in said parent application.

With these and other objects in view, reference 25 is made to the accompanying sheet of drawings which illustrates an embodiment of this invention with the understanding that detail changes may be made without departing from the scope thereof.

30 In the drawing—

Figure 1 is a view partly in front elevation and partly in diagram, illustrating an application of this invention as disclosed in said parent application.

35 Figure 2 is a view in longitudinal vertical central section of this improved switch, shown in the open position with parts shown in side elevation.

Figure 3 is a view similar to Figure 2 showing 40 this improved switch in closed position.

Figure 4 is a top plan view of Figure 1.

For a better understanding of the advantages and peculiar construction of this improved combined resistor and shunt switch, it is deemed advisable to first briefly describe a practicable commercial application of this novel switch before defining its peculiar construction. With this object in view, reference is made to Figure 1 of the drawing which shows in diagram the application 45 of this switch in controlling the operation of a reversing motor, as more specifically disclosed in this applicant's parent application, Serial No. 683,037, filed July 31, 1933, with the understanding that by so doing the use of this invention is 50 in no way limited to this single use.

To avoid damage, or unnecessary abuse to reversing motors, or equipment operated thereby, it is often necessary or desirable to provide a delay between the opening of the running circuit and the closing of the reversing circuit and vice versa. 5 The control of such motors is usually accomplished through remote control switches which open and close the motor circuits and additional mechanism is required to provide the delay necessary between the closing of the motor circuit and 10 the operation of the motor.

The additional mechanism is interposed between the source of the current and the motor and caused to function upon the opening and closing of the remote control switch to immediately open the circuit to the motor and thereafter allow a period for slowing up or stopping of the motor before closing the reversing circuit, to provide always a positive delay in the breaking of one motor circuit and making the reversing 20 circuit, following the operation of the remote control switch, regardless of how rapidly the control switch is caused to operate.

It is preferable in the delay switch operating mechanism to use the repulsion relay such as disclosed in this applicant's co-pending application, Serial No. 508,185, filed January 12, 1931, now Patent No. 1,973,925 of September 18, 1934, which is adaptable for use with either alternating or direct current or the relay disclosed in this application's co-pending application, Serial No. 500,747, filed December 8, 1930, which may be of the transformer type permitting the use of low voltage remote control equipment, and in connection with the relays to employ an electrical 35 resistor in the control circuit. The resistor contemplated may be any of the resistance elements, which offers great resistance to the passage of electric current therethrough when cold, but as its temperature increases, due to the passage of 40 current therethrough its resistance decreases until a large amount of current is passable. Such elements are known in the art and one known as Durhy, an electric furnace product having as its base silicon carbide with a very high dissociation temperature, is manufactured by the Globar Corporation of Niagara Falls, New York. 45

The control for a reversing motor shown in Figure 1 includes an electric motor M and two relays comprising a rectangular core C with a stationary primary coil P secured to the center of the upper leg thereof with movable secondary coils S mounted upon the same leg on each side of the stationary coil P. The switch carrying arms 1 are pivotally mounted at 1^b to the lower

leg of the core C and are each secured at their upper ends to their respective secondary coils. The arms I are extended downward on opposite sides of the lower leg to which they are pivoted 5 and the lower ends of each arm supports a motor switch MS and a shunt switch SS, as shown, so that the weight of said switches normally maintain the coils S in contact with the coil P.

The binding post 2 is connected to one side L 10 of the source of commercial current and also to one winding of the primary coil P, the other wire of which is connected through the binding post 3 to the return line L' commercial current. The binding post 2 is connected through the motor switch operated by the left hand coil S to binding post 4 and thence through the motor to operate it in the forward direction to the binding post 3. The binding post 2 is also connected through the motor switch MS on the right hand 20 side to the binding post 5 and thence through the motor to operate it in reverse direction to binding post 3. In this form, one end of the windings of each of the secondary coils S are connected through their respective shunt switches SS to binding post 6 and from thence to the remote control switch RC. The contact 25 7 adapted to be engaged by the remote control switch is connected to the other end of the winding of the secondary coil upon the right of the primary coil and the contact 8 adapted to be engaged by the remote control switch is connected to the other end of the secondary coil upon the left of the primary coil.

In this form, the shunt switches SS are identical and each one is a mercury tube switch especially constructed to act as both a resistance element and as a shunt switch, as shown in Figures 2, 3 and 4. As shown, the lower terminal 9 is provided with an offset 10 adapted to engage one 30 end of the resistor element R and the upper terminal 11 is brought down to contact the other end of the resistor R and hold the same firmly in position between the two terminals at the bottom of the mercury tube switch. The resistor is provided with metal caps RR to which the terminals are welded. By this construction when the remote control switch opens the circuit through a secondary coil, the weight of the switches carried thereby returns it to contact 35 with the primary coil and opens both of said switches, so that when the remote control switch reestablishes the circuit through the secondary coil, the current passes through the resistor in the open shunt switch causing a delay in the movement of the secondary coil until the resistor has increased sufficiently in temperature to allow sufficient current to pass therethrough to 40 repel said secondary coil, whereupon the motor 45

switch and shunt switches are closed. The closing action of the shunt switch causes the mercury 12 therein to contact the terminals 9 and 11 to establish the circuit through the resistor R and as the switch is tilted the mercury itself not only shunts out the resistor R but as it submerges the resistor R also has a cooling effect and accelerates the reduction in temperature of the resistor so that upon rapid switching of the remote control RC the delay, resulting from the heating 10 of the resistor, will not be shortened.

What I claim is:

1. A combined resistor and shunt switch including an envelope having terminals sealed in the walls thereof, an electrical resistor having a negative temperature coefficient interposed between the terminals to be always connected in circuit therewith, and a movable body of conducting fluid which, in one position of the switch, moves away from the resistor and terminals to be 15 completely out of contact therewith, and, in another position of the switch moves to submerge the resistor and shunt it.

2. The structure of claim 1 in which the terminals are engaged by the fluid before the resistor is submerged.

3. The structure of claim 1 wherein the terminals are simultaneously engaged and the circuit closed by the conducting fluid before the fluid engages the resistor.

4. In a mercury tube switch, a sealed glass envelope containing a movable body of mercury, electric terminals sealed in one end thereof one above the other, the upper terminal bent at an angle within the envelope to end in the same 35 plane and in line with the end of the lower terminal, said lower terminal offset within the envelope adjacent the wall thereof, and an electric resistor having a negative temperature coefficient interposed between said offset terminal and end 40 of the upper terminal to be always in circuit therewith, whereby when the mercury is contained in one end of the envelope, it is out of contact with the said terminals and resistor and upon flowing into the other end, the mercury 45 shunts the resistor and reduces its temperature.

5. A combined resistor and shunt switch including a tiltable mercury tube switch containing a body of mercury and two spaced apart terminals extending thereinto normally out of contact with the mercury, in combination with an electrical resistor having a negative temperature coefficient interposed between the terminals to be always in circuit therewith and to be free of said mercury upon tilting the switch in one direction 50 and be submerged and shunted by said mercury upon tilting the switch in the other direction.

IRA E. McCABE.
